SELECTIVE ADDRESSING MACHINE

Joseph Krell, Berlin-Zehlendorf, Germany, assignor to Adrema Maschinenbauges m. b. H., Berlin, Germany

Application February 7, 1938, Serial No. 189,200
In Germany February 20, 1937

9 Claims. (Cl. 101—58)

My invention relates to a device for affording visible indication of the plates to be printed and those to be skipped in a printing machine having checking and printing stations. The plates may be the printing plates of address-printing machines, and, more particularly, to a device of the kind described for printing plates equipped each with not less than one tab, for subdividing the supply of plates into groups to be printed, and groups to be skipped.

It is an object of my invention to provide an improved device of the kind referred to by which a more rapid operation is effected.

To this end, in combination with a track along which the plates equipped with a single tab, or any number of tabs, are moved past the checking and printing stations of a printing machine, I provide an exchangeable checking strip, checking means, normally not less than one projection, which is integrally formed with, and detachable from the strip corresponding to the tabs of a group of plates to be printed, and a holder at the checking station for presenting the checking means or detachable projections of the strip to the tabs on the plates.

In address-printing machines having printing plates with tabs and manually operated means for skipping those plates that are not to be printed, it has already been proposed to partly cut away one of the rails of the track at the checking station so as to expose the tabs on the printing plates and to allow the operator to have them printed or skipped, as indicated by the tabs.

With the comparatively high operating speed of address-printing machines it is difficult for the operator to decide immediately whether a plate which arrives at the checking station is to be printed or skipped, and errors may occur. This is practically eliminated by my device which facilitates the checking operation so much that the operator can see at a glance which plate is to be printed.

It is another object of my invention to provide an improved checking strip.

To this end, I make the strip—which preferably consists of Celluloid or some other similar material, preferably colored—with integrally formed projections arranged at one side of the strip and slightly creased at the root so that they are easily detachable. There are as many projections on the strip as tabs can be secured to each plate, and those projections that are not required for a given group of printing plates, are broken off.

In the accompanying drawings, part of an ad-

dress-printing machine embodying my invention is illustrated by way of example.

In the drawings:

Fig. 1 is a perspective illustration showing those parts of the machine which are related to the 5 invention,

Fig. 2 is a perspective illustration of the checking station, showing the holder for the strip ready for the final securing of the strip,

Fig. 3 is a perspective illustration, drawn to a 10 larger scale and showing the parts of the strip holder separately,

Fig. 4 is a section on the line IV—IV in Fig. 3,

Fig. 5 is a vertical longitudinal section of the 15 assembled holder, on the line V—V in Fig. 1,

Fig. 6 is a plan view of a checking strip, as made, and

Fig. 7 shows the strip ready for use, i. e., with all projections except two broken off.

Referring now to the drawings, 1 is the table of 20 the address-printing machine, and 2 is its oscillating printing arm which is operated by hand or by any suitable mechanical means, not shown. Its printing head 3 is equipped with the usual printing pad.

4 is a hopper for the printing plates 5. The 25 hopper consists of a channel-section member at one side, and a flat member at the other. The members are so arranged that the printing plates in the hopper are easily accessible. The printing plates, in manner known in this art, are fed in their longitudinal direction and in succession along a track formed by a pair of parallel rails 1 and 1', and intermittently moved past the 30 checking station 5', the printing station 9 where an inked ribbon 8 is provided, and a final section 35 of the track, to be delivered to a container 10. Any suitable means, not shown, may be provided for moving the plates along the track intermittently, and for skipping those plates that are 40 not to be printed.

A single tab, or any desired number of tabs, two tabs 6 being shown by way of example, are secured to one of the guiding edges of each printing plate 5 and are preferably of distinct colors, 45 for subdividing the printing plates into groups to be skipped, and groups to be printed.

Only those printing plates which are allotted to a given group by a definite tab 6, or a combination of tabs, will be printed at the printing 50 station 9, and such plates are not selected by automatic means but by the operator checking the plates at the station 5'.

At the checking station, the rail 1 at the right of the track—as viewed in the direction in which 55

the printing plates 5 move along the track—is omitted or recessed so that the tab, or tabs, 6 are displayed at this point when the printing plates 5 are at the checking station, as best seen in Fig. 1.

As described above, a device in which the tabs are merely displayed is not proof against errors. My invention therefore provides means for checking the plates at the checking station, i. e., for 10 comparing them with the projections left on the checking strip. By these means it is made easy for the operator to pick out, at a glance, those plates which are to be printed.

The means is the holder illustrated particularly in Figs. 3, 4, and 5. It is arranged at the right-hand side of the checking station 5' where the rail 7 is omitted, or recessed. A plurality of pins project upwardly from the table 1, and the several parts of the holder, and the checking strip 12, 20 are placed on the pins with suitable holes. Preferably, more than two pins are provided, and spaced at different distances from each other. In the present instance, three pins 14, 15, and 16 are arranged, and the pin 14 at one end is spaced 25 further away from the intermediate pin 15 than the pin 16 at the other end of the holder. The parts of the holder have holes to fit on the pins, and similar holes are made in the checking strip 12. On account of the non-uniform spacing 30 of the pins, the parts of the holder can only be placed on the pins in a definite position, and so the arrangement is foolproof.

Preferably, an insertion 19 is placed on the pins 14, 15, and 16 as the base of the holder. The insertion is a flat strip, of Celluloid or other suitable material, and of such width that it projects from the holder at the inner side of the track and is below the tab, or tabs, 6 of the printing plates 5 when they are at the checking station 5'. The 40 projecting portion of the insertion 19 is painted white, or some other distinctive color, so that it contrasts strongly with the tab, or tabs, above it. A straight-edge 11, with its inner or guiding edge 24 arranged in parallel relation to the path of the edges of the printing plates 5 where the tab, or tabs, 6 are attached, and preferably painted white, like the insertion 19, is placed on the pins 14, 15, and 16 above the insertion, and secured by a pair of screws with sunk heads. 45 The ends of a U-shaped holder 18 are permanently secured to the ends of the straight-edge 11. The holder engages above the edges of the printing plates 5 where the tab, or tabs, 6 are secured and defines, together with the inner edge 24, a space or window in which the tab, or tabs, are exposed to view. At the same time, the holder 18 guides the printing plates. The pins 14, 15, and 16 are so long that they project from the upper face of the straight-edge 11 and receive 50 the checking strip 12 and a bar 13 by which the checking strip is held on the straight-edge. The checking strip 12 which, as mentioned, is made of Celluloid, or similar material, and preferably colored, is made with as many checking means or 55 integrally formed, detachable as there are points on the printing plates for the reception of a tab, or tabs, 6. In the present instance, it has been assumed that there are fourteen such points on each printing plate, and so the checking strip, as 60 made and as shown in Fig. 6, has fourteen projections 23 numbered from "1" to "14" at its inner side, i. e., that side which faces the track for the printing plates 5. Preferably, the projections 23 are slightly creased at the roots to 65 facilitate their separation from the body of the

strip. Holes 20, 21, and 22 serve for placing the strip on the pins 14, 15, and 16 in the proper position, i. e., with the projections 23 toward the inner side of the track, this being enforced by the differential spacing of the pins and holes, as described. It is not necessary but it may be desirable under certain conditions, to number the checking means or integrally formed, detachable projections consecutively in conformity with the tab-receiving points of the printing plates, as 10 shown for the projections "1" to "7" in Fig. 6. The numerals, and the creases at the roots of the projections, indicate the upper side of the strip 12 which must be on top when the strip is placed 15 in the holder.

If it is desired to print only the plates of a certain group, for instance, the plates having tabs 6 at the fourth and tenth points, and to skip all others, the projections 23 are broken off with the exception of those numbered "10" and 20 "4" and designated by the numerals 23' and 23'', respectively, in Fig. 7. The operator knows that only those printing plates 5 must be printed with which the position of the tabs 6 corresponds to that of the projections 23', 23'' on the checking 25 strip 12, and is able to ascertain at a glance whether a printing plate arriving at the checking station 5' has its tabs positioned in conformity with the position of the projections 23' and 23''. Fig. 2 shows such a printing plate at the check- 30 ing station.

When the strip 12 has been placed on the pins 14, 15, and 16 in the proper position, the bar 13 is placed on the pins to weigh down the strip. The inner face of the bar 13 is preferably chamfered as shown at 25 in Fig. 4, to further improve the visibility of the projections and tabs. By the non-uniform spacing of the pins 14, 15, and 16, and consequently of the holes 20, 21, and 22 in the checking strip 12, as described, the 40 operator is under the necessity of placing the strip 12 onto the straight-edge 11 in the proper position which is not positively assured if the pins are equidistant since then the strip might be inserted the wrong way. The bar 13 has bores in 45 its lower face for the reception of the pins 14, 15, and 16, and is comparatively heavy.

In the example illustrated, only those printing plates will be printed whose tabs 6 are in positions corresponding to the position of the projections 23' and 23'' on the checking strip 12. If, as 50 shown in Fig. 1, a printing plate arrives at the checking station whose tabs 6 do not register with the projections 23' and 23'', the operator sees this with a swift glance and knows that this plate must not be printed but skipped after arriving at the printing station. If, on the other hand, as shown in Fig. 2, a printing plate arrives at the checking station whose tabs register with the projections 23', 23'', the operator knows that 55 this plate must be printed after having moved as far as the printing station.

Obviously, an ample supply of checking strips 12 must be kept in stock so that strips will always be available for the various combinations of tabs 65 required to which they are adapted by breaking off those checking means, or integrally formed, detachable projections, that are not required.

I claim:

1. In a device for affording visible indication 70 of the plates to be printed and those to be skipped in a printing machine having checking and printing stations, a tab on each printing plate of a supply, for subdividing the supply into groups to be printed and groups to be skipped, a track 75

- along which the plates are moved past the checking and printing stations of the machine, an exchangeable checking strip, integrally formed, detachable projections on the strip 5 arranged to correspond to the position of the tabs on the plates belonging to a group to be printed, and a holder at the checking station for presenting the projections of the strip to the tabs on the plates.
10. 2. In a device for affording visible indication of the plates to be printed and those to be skipped in a printing machine having checking and printing stations, a tab on each printing plate of a supply, for subdividing the supply into groups 15 to be printed and groups to be skipped, a track along which the plates are moved past the checking and printing stations of the machine, an exchangeable checking strip, an integrally formed, detachable projection on the strip 20 arranged to correspond to the position of the tabs on the plates belonging to a group to be printed, and a holder at the checking station for presenting the projection to the tabs on the plates.
25. 3. In a device for affording visible indication of the plates to be printed and those to be skipped in a printing machine having checking and printing stations, a tab on each printing plate of a supply, for subdividing the supply into 30 groups to be printed, and groups to be skipped, a track along which the plates are moved past the checking and printing stations of the machine, an exchangeable checking strip, integrally formed, detachable projections on the strip 35 arranged to correspond to the position of the tabs on the plates belonging to a group to be printed, a holder at the checking station, and means on the holder for presenting the projections of the strip to the tabs on the plates only 40 in the proper position with respect to the tabs.
4. In a device for affording visible indication of the plates to be printed and those to be skipped in a printing machine having checking and printing stations, a tab on each printing plate of a supply, for subdividing the supply into groups to be printed and groups to be skipped, a table, a track on the table along which the plates are moved past the checking and printing stations of the machine, more than two 45 pins projecting from the table at the checking station and pitched at different distances from each other, an exchangeable checking strip having perforations for threading it on the pins, checking means on the strip arranged to correspond to the position of the tabs on the plates 50 belonging to a group to be printed, and a holder located by the pins for presenting the checking means of the strip to the tabs on the plates.
5. In a device for affording visible indication of the plates to be printed and those to be skipped in a printing machine having checking and printing stations, a tab on each printing plate of a supply, for subdividing the supply into groups to be printed and groups to be skipped, a track along which the plates are moved past the 55 checking and printing stations of the machine, a straight-edge arranged in parallel relation to the track at the checking station, a downholder for the plates secured to the straight-edge and defining, with the straight-edge, a space in which the tabs on the printing plates are exposed to view, pins projecting through the upper side of the straight-edge, an exchangeable checking strip 60 having holes for the reception of the pins, checking means on the strip arranged to correspond to the position of the tabs on the plates belonging to a group to be printed, and a bar adapted to be placed on the upper ends of the pins for holding the strip down on the straight-edge.
6. In a device for affording visible indication of the plates to be printed and those to be skipped in a printing machine having checking and printing stations, a tab on each printing plate of a supply, for subdividing the supply into groups to be printed and groups to be skipped, a track along which the plates are moved past the 65 checking and printing stations of the machine, a straight-edge arranged in parallel relation to the track at the checking station, a downholder for the plates secured to the straight-edge and defining, with the straight-edge, a space in which the tabs on the printing plates are exposed to view, pins projecting through the upper side of the straight-edge, an exchangeable checking strip having holes for the reception of the pins, checking means on the strip arranged to correspond to the position of the tabs on the plates belonging to a group to be printed, and a bar adapted to be placed on the upper ends of the pins for holding the strip down on the straight-edge.
7. In a device for affording visible indication of the plates to be printed and those to be skipped in a printing machine having checking and printing stations, a tab on each printing plate of a supply, for subdividing the supply into groups to be printed and groups to be skipped, a track along which the plates are moved past the checking and printing stations of the machine, an exchangeable checking strip, detachable projections arranged at one side of the strip and equal in number to the number of points where tabs can be secured to the plates, and a holder at the checking station for presenting to the tabs on the plates those projections which are still on the strip after it has been adapted to the position of the tabs on the plates belonging to a group to be printed.
8. In combination, printing plates having tabs thereon, a device for affording visible indication of the plates to be printed and those to be skipped, said device including a strip, and a row of integrally formed detachable projections at one side of said strip.
9. In combination, printing plates having tabs thereon, a device for affording visible indication of the plates to be printed and those to be skipped, said device including a strip, and a row of integrally formed detachable numbered projections at one side of said strip.

JOSEPH KRELL.
